J. L. HOLTON.
AUXILIARY AIR SUPPLY DEVICE FOR GASOLENE ENGINES.
APPLICATION FILED DEC. 6, 1911.

1,070,131.

Patented Aug. 12, 1913.

UNITED STATES PATENT OFFICE.

JOHN L. HOLTON, OF LISBON, OHIO.

AUXILIARY AIR-SUPPLY DEVICE FOR GASOLENE-ENGINES.

1,070,131.

Specification of Letters Patent. Patented Aug. 12, 1913.

Application filed December 6, 1911. Serial No. 664,234.

To all whom it may concern:

Be it known that I, JOHN L. HOLTON, a citizen of the United States, residing at Lisbon, in the county of Columbiana and State 5 of Ohio, have invented a new and useful Auxiliary Air-Supply Device for Gasolene-Engines, of which the following is a specification.

This invention has reference to improvements in auxiliary air supply devices for gasolene engines, and is designed to provide a device which may be applied to the intake manifold of a gasolene engine between the carbureter and the intake valve to cause an 15 automatic regulation of the air supply in accordance with the speed of the engine; and to provide a priming means for starting the engine and means for decarbonizing the engine as needed.

20 To these ends the device comprises a valve structure which may be readily adjusted as to the degree of opening and which when installed will cause an injection of air into the intake manifold of the engine in fine streams, 25 thereby thoroughly intermixing with the charge traveling from the carbureter to the engine, and the device is so arranged that a priming quantity of gasolene may be placed therein to be drawn by the turning over of 30 the engine into the cylinder for the initial starting, and since kerosene is a softening agent for carbon deposits in gasolene engines, the device provides a means whereby kerosene may be introduced in any desired 35 quantity into the engine while running to cause a softening of any carbon deposits so that the latter are blown out of the engine with the exhaust, wherefore by an occasional application of kerosene the engine may be 40 kept practically free from carbon deposits.

The invention will be best understood from a consideration of the following detailed description taken in connection with the accompanying drawings forming a part 45 of this specification, with the understanding that while the drawings illustrate a practical form of the invention the latter is susceptible of various changes and modifications and, therefore, the invention is not

limited to any strict conformity with the 50 showing of the drawings, but the structure may be variously changed and modified so long as the salient features of the invention are retained and the result sought is obtained.

55 In the drawings:—Figure 1 is an elevation of the attachment showing a small section of the manifold of an engine in longitudinal section. Fig. 2 is a central section through the attachment shown in Fig. 1. Fig. 3 is a central section through the intake end of the device but drawn to a larger scale than the other figures. Fig. 4 is a section on the line 4—4 of Fig. 1 with the retaining device for the adjustable cap member moved away from the cap beyond the point of section to show the inner face of said retaining member, distant parts being omitted. Figs. 5 and 6 are plan views of modified forms of 60 inlet valve disks.

65 Referring to the drawings there is shown in Fig. 1 a conduit 1 which may be taken as illustrating in part the manifold of a gasolene engine between the carbureter and the intake valve of the engine, and as the device of the present invention is designed as 70 an attachment capable of application to the manifolds of installed engines it is deemed unnecessary to show more than a portion of the manifold.

75 The device of the present invention includes a valve 2 terminating at one end in a threaded neck 3 designed to be attached to the manifold 1 by means of a tapped passage 80 formed through the wall of the manifold. Secured to the end 3 of the valve is a tube 4 terminating at the end remote from the valve in a head 5 and intermediately this tube is provided with numerous perforations 85 6. The tube 4 is of a diameter to enter a 90 countersunk portion of the bore of the threaded end 3 of the valve body, while the head 5 is expanded to approximately the same diameter as the threaded end 3 and between these two points the tube 4 is surrounded by a gauze sleeve 7 wherefore the 95 passages 6 discharge into a chamber defined by the tube 4 and sleeve 7, and any fluid dis-

charged into this chamber will find its way into the manifold in a multitude of small streams through the interstices of the gauze.

The movable part or spigot of the valve 2 has its stem connected to a rod 8 which in the installed device extends to a ready point of access and in an automobile this point of access will be adjacent the dash so that the operator may manipulate the valve as found necessary. The valve 2 while shown in the drawings as of the ordinary pet cock type, may be of any suitable type.

The manifold 1 is customarily upright and the valve 2 is usually applied so that the tube 4 is approximately horizontal where entering the manifold and in any event extends transversely of the manifold. Under these circumstances there is applied to that end of the valve 2 remote from the threaded end 3 an elbow 9 which at the end remote from the valve 2 is entered by the threaded end 10 of a tube or pipe 11, which when in installed position is upright or approximately so. The end of the tube 11 remote from the threaded end 10 is expanded, as indicated at 12, and this expanded end has external screw threads 13 adapted to receive an internally threaded annular flange 14 of a cap 15, which latter is contracted into an axially extended neck 16 on the side remote from the flange 14 and the cap 15 is provided with a milled edge 17 for convenience of manipulation.

The flange 14 of the cap 15 at the edge remote from the cap is formed with teeth or notches 18 which may be in the form of a circular series extending entirely about the corresponding edge of the flange, while on the tube 11 there is mounted a holding member 19 in the form of a hollow cup of an internal diameter to embrace the expanded portion 12 of the tube 11, and on the free edge of this cup or holding member 19 are oppositely located teeth 20, these teeth being usually two in number, although a single tooth will under some circumstances answer and a greater number of teeth may be employed. The holding member 19 is also provided with finger pieces 21 preferably on opposite sides and projecting axially from the holding member in position to be readily grasped by the fingers.

The pipe or tube 11 is provided with longitudinal flat portions 22 preferably on opposite sides, although a single flat portion will answer and the cup or holding member 19 is similarly shaped where traversed by the tube 11, so that the holding member is prevented from rotating on the tube 11, but may be readily moved lengthwise thereof. In order to maintain the holding member against the expanded portion or head 12, the tube 11 is surrounded by a spring 23 at one end engaging the cup 19 and at

the other end engaging in a socket member 65 24^a which may be brazed or soldered or otherwise connected to the tube 11 adjacent the threaded end 10 thereof in fixed relation thereto.

The cap 15 has lodged therein a valve 24 composed of two disks 25, 26 held together by a bolt 27 axial thereto, and these disks are each provided with passages 28, 29, respectively, which may be brought into full matching relation, or the disks may be turned axially so that the effective area of the passages 28 and 29 may be reduced. The cap 15 is so related to the head 12 that the valve 24 has a limited play within the cap seating against the cap adjacent the neck 16 in one direction of movement and seating against the head 12 at the other limit of its movement. The valve 24 has secured thereto by the bolt 27 a spring 30 which when the parts are assembled extends into the expanded end 12 of the tube 11 and bears thereagainst, the tendency of the spring 30 being to hold the valve 24 seated against the cap 15 and the parts are so arranged that when the valve is seated against the cap 15 the ports or passages 28 and 29 are closed by the cap 15 and consequently flow of air or other fluid into the pipe 11 through the neck 16 is prevented.

Let it be assumed that the valve 2 is open, wherefore, except for the presence of the valve 24, there is a free passage from the neck 16 through the pipe 11, elbow 9, valve 2, and pipe 4 to the interior of the manifold 1.

It frequently occurs that in the operation of gasoline engines, especially automobile engines, the carburetor mixture is not sufficiently intimate and also is too rich, wherefore the entrance of additional air is of advantage for diluting the mixture and, moreover, by causing the entrance of this additional air into the mixture coming from the carburetor, in a multitude of fine streams breaks up the richer mixture and causes an intimate association of the particles of the mixture resulting in increased power in the engine. The injection of additional air, however, must be in accordance with the speed of the engine and also with the size and character of the engine. For this purpose the valve 24 is provided so that the air flows into the engine only when the suction causing the flow of the charge through the manifold 1 reaches a degree determined by the position of the cap 15 on the head 12, whereby the tension of the spring resistant to the opening of the valve 24 is adjusted. This is brought about by screwing the cap 15 to a greater or less extent on the head 12, the holding cup 19 being withdrawn from engagement with the cap 15 by moving it along the pipe 11 against the action of the

spring 23, and after the cap 15 has been adjusted to the desired point the holding member 19 is released and at once locks the cap against further movement except at the will 5 of the operator, the holding member 19 effectually locking the cap against accidental turning.

The valve 24 is capable of further modification as to the flow of air through it by the 10 relative turning of the disks 25 and 26, whereby the ports made up of the coating passages 28 and 29 are made effectively larger or smaller. The action of the valve 24, therefore, depends upon the tension of 15 the spring 30 and the effective size of the ports made up of the passages 28 and 29. Furthermore, intermixture of the fluid entering through the device into the manifold with the charge passing through the manifold 20 is rendered more effective by the presence of the gauze sleeve 7 which breaks up the incoming streams issuing from the perforations 6 into a multitude of minute streams.

25 In the installed device the neck 16 is upright and when the engine is not running the valve 24 is closed, wherefore the neck 16 constitutes a cup into which a suitable quantity of gasoline may be introduced and 30 by turning over the engine with the valve 2 open this gasoline is sprayed into the manifold 1 in conjunction with air coming through the neck 16 when emptied of gasoline, and such air also flows along the manifold 1 thus forming an initial charge which 35 is carried into the engine and compressed and exploded, giving an initial impulse to the engine which by the power thus furnished will rotate enough times to cause the 40 proper operation of the carburetor and the continued running of the engine.

Explosion engines are often liable to accumulations of carbon in the cylinders and ports by deposition from the exploded 45 charges, and such carbon is quite readily softened by the use of kerosene. When it is desired to clean out the deposited carbon from the engine the valve 2 is opened and kerosene is poured into the neck 16 while 50 the engine is running, the pouring being continued until a suitable quantity of kerosene, say a pint, more or less, is drawn into the manifold 1 and from thence into the cylinder or cylinders of the engine, where 55 it attacks the carbon and softens the same to such an extent that the force of the exhaust will carry the softened and loosened carbon from the cylinders and valves to the atmosphere.

60 The disks 25 and 26 of the valve 24 may be otherwise shaped than shown in Figs. 2 and 3, for instead of ports in the form of perforations or passages 28 and 29, each disk may have peripheral angle notches 28^a as in

Fig. 5 or rounded notches 29^a as in Fig. 6, 65 the disks of the valve being adjustable one relative to the other to vary the effective area of the notches or peripheral passages as in the form shown in Figs. 2 and 3.

What is claimed is:—

1. An attachment for explosion engines, comprising a duct having at one end multi-apertured means introducible into the manifold of the engine between the carburetor and the explosion chamber of said engine, 75 and at the other end having a valve seat provided with a freely open prolongation to form a receptacle for liquid, a valve in operative relation to the valve seat and in normally closing relation to the corresponding 80 end of the duct and constituting the bottom of the receptacle, and elastic means on the side of the valve remote from the receptacle and tending to hold the valve in the closed position and also yieldable to the action of 85 suction produced in the manifold.

2. An attachment for the manifolds of explosion engines between the carburetor and explosion chamber of the engine, including in its construction a valve, a valve casing housing the valve, a support for the casing along which the latter is adjustable in the direction of movement of the valve in the casing, and locking means for holding the casing in adjusted positions, the valve 90 having a normal constraint to the closed position and provided with ports for the passage of fluid through the valve when the latter is in the opened position.

3. An attachment for gasoline engines 100 adapted to be applied to the manifold between the carburetor and explosion chamber of the engine, including in its construction a pipe having an expanded end threaded externally, a cap adapted to said threaded end 105 and provided with an axial passage therethrough, a valve comprising two ported disks movable one on the other to determine the effective area of the ports, a spring between the valve and the expanded end of 110 the pipe, and means for locking the cap in adjusted positions on the expanded end of the pipe to determine the tension of the spring.

4. An attachment for explosion engines 115 comprising in its construction a conduit having one end adapted to be inserted in the manifold of an explosion engine between the carburetor and the explosion chamber of the engine, said end comprising a perforated pipe with a gauze envelop spaced therefrom, a valve in the conduit adapted to be located exterior to the manifold, and another valve in the conduit at the intake end thereof, said last named valve being yieldable to suction produced in the manifold to admit fluid to the conduit.

5. An attachment for an explosion engine

adapted to be applied to the manifold of the engine between the carbureter and explosion chamber thereof, said attachment including in its construction a conduit having at one 5 end a valve with a normal tendency toward the closed position and yieldable to suction produced at the other end of the conduit, the said valve being inclosed in a valve casting provided with an exterior upright neck 10 open at the upper end and constituting a re-

ceptacle for liquid to be introduced into the conduit.

In testimony, that I claim the foregoing as my own, I have hereto affixed my signature in the presence of two witnesses.

JOHN L. HOLTON.
